UNITED STATES PATENT OFFICE

166,045

BELT SANDER

Fred Williams Moore, Greenfield, Mass., assignor
to Millers Falls Company, Greenfield, Mass., a
corporation of Massachusetts

Application October 18, 1951, Serial No. 17,011

Term of patent 14 years

(Cl. D37—1)

To all whom it may concern:

Be it known that I, Fred W. Moore, a citizen of the United States, residing at 31 Lovers Lane, Greenfield, in the county of Franklin and State of Massachusetts, have invented a new, original, and ornamental Design for a Belt Sander, of which the following is a specification, reference being had to the accompanying drawing, forming a part thereof.

Figure 1 is a side elevation of a belt sander, showing my new design;

Figure 2 is a side elevation from the opposite side; and

Figure 3 is a rear end elevation.

I claim:

The ornamental design for a belt sander, as shown.

FRED W. MOORE.
